MASSAGE DEVICE

William G. Smith, Portland, Oreg.

Application November 1, 1949, Serial No. 124,881

9 Claims. (Cl. 128—25)

1

This invention relates to a power operable massage device especially useful in connection with medical treatments for human ailments, such as "polio" that is so devastating in its effects, where massage of long continued duration is indicated for large areas of the body of the person being treated.

The objects of the invention are to provide a mechanical device capable of applying massage to selected portions of the human body, with the endurance of the machine rather than that of a trained masseur, and at the same time to apply massage effects of a variable vigor and with variable intermittent or pulsation effects.

Drawings accompany and form a part of this disclosure in which a sheet containing Figs. 1 to 4 inclusive are directed to the invention and Figs. 5 and 6 on a second accompanying sheet delineate a suitable control valve to produce a variable pulsating effect. This control valve is believed to be old and is shown merely as means for making the invention operable. It is not claimed herein.

In the drawings,

Fig. 1 is a separate machine, so formed as to be available for massaging the human arm; with a part broken away;

Fig. 2 is a section taken on the plane 2—2, Fig. 1;

Fig. 3 is an enlarged sectioned vacuum cup showing its relationship to supporting structure when in inactive normal position, for example the individual vacuum cup indicated by numeral 1 in Fig. 1;

Fig. 4 is a view showing a cross section of a different shaped massage device, applied against a form representing the outline of a portion of the back of a human figure, to be further explained;

Fig. 5 is a sectional view of a suitable control valve taken on the plane 5—5 of Fig. 6; and

Fig. 6 is a sectional view of the structure shown in Fig. 5, taken on the plane 6—6 of Fig. 5.

Describing the figures of the drawings in greater detail: Numeral 2 represents a rigid outer wall and numeral 3 identifies a spaced rigid inner wall; numeral 4 indicates an end closure, which, when the vacuum cups 1 with their tubular shanks 11 are in place, constitutes boundary means for an airtight vacuum chamber 5. The vacuum chamber will be selectively energized by vacuum producing means symbolized by the arrow V which is connected with the vacuum chamber 5 by means of the conduit 6. The shanks 11 and the vacuum cups proper, 1, are made of very

2

flexible rubber and are hermetically joined and sealed to the flexible rubber wall 7, which will be joined to the end closures 4. The tubular shanks 11 of the vacuum cups 1 extend across the space 8 between the walls 3 and 7, being hermetically sealed by suitable means to both walls 3 and 7. The space 8 between said rubber wall 7 and the rigid inner wall 3, is a suitable pressure chamber that will be supplied with pressure, either steady or variable as may be desired, through a suitable control valve from a pressure producing means symbolized by the arrow P, by way of the tube 9.

In Fig. 4, an arbitrary line 12 will be assumed to represent a region of the back of a human needing that part of the body massaged and the construction is according to the same principle, with the vacuum chamber 5, the pressure chamber 8, between the rigid wall 3 and the flexible rubber wall 7. The pressure chamber 8 in this figure will be supplied with a suitable tube 9, not shown in the fragmentary view in this illustration.

Other and differently shaped units may obviously be constructed to be adaptable for applying massage to the lower limbs and with sufficiently powerful vacuum and pressure apparatus, it is evident that a multiplicity of pressure and vacuum machines will not be necessary.

The pressures in the pressure chamber 8 will be of sufficient magnitude to bend the flexible wall 7, after the manner shown, to bring the suction cups 1 into contact with the flesh surface to be treated by massage, stretching the shanks 11 in some cases to bring vacuum cups 1 into contact. It is obvious that a kneading of the body parts can be accomplished by a pulsating pressure application alone and that by conjoint use of the vacuum and pressure apparatus selective application of massage over a wide range is easily within the selection of the operator.

I will now describe the regulating valve, designated as suitable, but no part of the present invention and included merely to show a complete operative construction.

There are two control valves, one each for vacuum and pressure, numbered respectively 15 and 16, mounted on a common valve stem 17, and having coaxial valve bushings 18 and 19. The valves 15 and 16 are spool valves that have valve cooperating parts at each beveled portion of the spools to which the lead lines from the numerals 15 and 16 are directed, with barrel portions 20 and 21. Formed at their ends, the bushings 18 and 19 have valve seats 22 and 24 at one end and 23 and 25 at the other. All of the fore-

going mechanism is mounted in properly machined seats in a casing 26. The valves 15 and 16 are moved by a lever 27 as will be explained.

The vacuum valve 15 is shown to be open, permitting air evacuation of the plural suction cups and their adhesion to a corresponding part of a patient's body; the vacuum influence being applied through the tube 28, the chamber 29, the conduit 30, the annular channel 31, the valve chamber 32 and the tube 33 to the vacuum space 10 5 in any given massage unit such as the unit shown in Figs. 1 or 4. After a predetermined interval, or under certain conditions, the valve 15 and with it the valve 16 will snap over under influence of the spring 34, which is under tension in either position of the actuator 35-36, 15 which is movable in the double ended cylinder 27-38, the central portion of which is open to atmosphere by the lever slot 39, which likewise puts the chamber 40, between the halves 15 and 20 16 in communication with atmosphere for exhaustion.

The connecting bar 41 of the actuator 35-36 is provided with a slot 42 within which is a pin 43, which serves as a fulcrum against which the lever 27 may find a somewhat cushioned reaction.

It will be noted that when there is pressure in the closed cylinder 38 and vacuum of some degree sufficient to cause adherence of the vacuum cups 1 exists in the cylinder end 29, the tendency of the actuator will be to hold the valves in the position shown with the vacuum cups actuated and pressure shut off through the port 44, which is of relatively small cross section and capacity; but still supplied with pressure through the port 45, which should have enough larger capacity to maintain some pressure against the flexible rubber wall 7, and is in communication with the pressure end of the cylinder 38.

This can give a steady adherence of the vacuum cups and a pulsating movement of the flexible rubber wall of a magnitude determined by the pressure and volume of the pressure producer, which will ordinarily be of the fan type, as the pressures required are not large.

When the lever 27 is moved, either manually or by a suitable mechanical apparatus to be attached and connected to the hole 46 in the lever 27, the pulsating effect may be varied widely.

This control valve system may be considered as schematic only and only to indicate that variable systems of massage may be applied with my machine by variable control means.

The invention resides in my arrangement of the flexible rubber wall and the suction cups to produce a variable massage effect on the flesh to which it is applied.

It will also be at once apparent that the whole device can be easily washed with a disinfecting fluid and subsequently dried by circulating the fluid followed by warm air.

Having fully disclosed my invention so that it can be made and used, what I claim as new and desire to secure by Letters Patent, is:

1. A machine for applying massage therapy to a portion of human body, comprising a plurality of suction cups, a yieldable mounting therefor comprising a wall-like rubbery structure, 70 pneumatic pressure retaining means of which said structure is a part and movable to carry said mounted cups against a body surface under influence of pneumatic pressure, and elastic means for reacting against said pressure when 75

it is decreased and vacuum energy means operatively connected to said suction cups.

2. A machine for applying massage therapy to selected portions of a human body, comprising groups of suction cups, a common rubbery mounting for each group of cups, pneumatic means of which said rubbery mounting is a part for varying the pressure of said cups against said portions of a body, and vacuum means independent of said pressure varying means for applying vacuum energy to the cups of a group of cups.

3. A massage machine, comprising a casing shaped to conform to a portion of a body surface, said casing comprising an outer wall member, a rigid wall spaced inside of said outer wall defining a vacuum chamber therebetween, said inner wall provided with a plurality of openings, rubbery vacuum cup shanks sealed in said openings, a rubbery wall next inside said inner wall through which said shanks pass in sealed relationship, thus defining a pressure chamber, and a vacuum cup made integral with the free end of each shank.

4. A massage machine, comprising a casing formed with body contact intermediate and outer surface elements, said body contact surface comprising a plurality of rubbery vacuum cups adapted to attach to epidermal surfaces under vacuum influence, an individual elongated rubbery hollow shank made integral with each vacuum cup, a vacuum chamber with which the outer ends of each shank is in open communication, and a rubbery, flexible wall through which each shank passes in sealed relationship to define a pneumatic pressure chamber in closely adjacent position to said vacuum cups.

5. A double acting machine for massage therapy, comprising a casing shaped for placement near to a portion of body surface, said machine comprising a suitable vacuum chamber formed with a rigid wall, a pressure chamber next adjacent said rigid wall, said pressure chamber expandible by reason of an expandible wall spaced from said rigid wall, a plurality of vacuum cups mounted on the outside of said expandible wall, and hollow elastic shanks sealed to and in communication with the interior of each of said vacuum cups, said shanks sealed to both of said walls, spanning the space therebetween, with the open ends of said hollow shanks inside of said vacuum chamber.

6. A machine for massage therapy, comprising a casing, vacuum and pressure chambers formed within said casing, said pressure chamber having a rigid wall that is common with said vacuum chamber, a spaced rubbery wall forming a boundary defining a dimension of said pressure chamber, and a plurality of vacuum cups sealed on the external surface of said rubbery wall with their cup surfaces in generally uniform contour with cups outwardly, each of said vacuum cups having an integral hollow shank traversing said pressure chamber and in sealed communication with said vacuum chamber.

7. A machine for applying double acting massage therapy to a portion of a human body, comprising a plurality of closely spaced rubbery vacuum cups, said vacuum cups made integral with elongated tubular rubber shanks, a rubbery wall through which said shanks pass in sealed relationship, a vacuum chamber with which said shanks are in sealed communication, and closure members joined with said rubber wall to com-

plete a tight pneumatic pressure chamber, through which said shanks pass to communicate with said vacuum chamber, said shanks resilient to return said rubber wall to normal position in the absence of pressure and exert a lift on vacuum cups already attached by suction to a body surface.

8. A massage device for a limb of a human body, comprising a generally tubular casing, said casing enclosing a tubular vacuum chamber inside said casing, means for applying vacuum effects thereto, a rigid tubular wall defining the inner boundary of said vacuum chamber, a pressure chamber formed next inside of said vacuum chamber by a spaced flexible inner tubular wall, a plurality of vacuum cups made integral with elongated tubular shanks of soft stretchable rubbery material, said shanks extending across said pressure chamber and being hermetically sealed to said rigid tubular wall and in open communication with said vacuum chamber, said elongated shanks sealed to said flexible inner wall with the vacuum cups in position to attach to a limb surrounded by the tubular casing by vacuum, and end closure members for said chambers.

9. A machine for massage therapy, comprising a vacuum device for placement in contact relationship with a body surface, a plurality of

vacuum cups spaced to constitute a body contact surface, said vacuum cups having integral elongated rubbery tubular shanks, an outer rigid wall of said device, a rigid inner wall spaced from said outer wall, a flexible inside wall spaced from said last named wall, end closures for said walls, means for establishing vacuum between said inner and outer walls, and means for producing pressure between said rigid inner wall and said flexible inside wall, said vacuum cups by their tubular shanks being in communication with said vacuum chamber and sealed against pressure from said pressure chamber.
